UNITED STATES PATENT OFFICE

RICHARD K. HOHMANN, OF BROOKLYN, NEW YORK, ASSIGNOR, BY MESNE ASSIGNMENTS, TO GOTHAM KNITBAC MACHINE CORPORATION, OF NEW YORK, N. Y., A CORPORATION OF DELAWARE

KNITTING NEEDLE

Application filed August 2, 1928. Serial No. 296,909.

This invention relates in general to knitting needles of the type employed in the machine for repairing runs in fabrics as disclosed in the copending application of William H. Leavin and Samuel B. Leavin, Serial No. 248,806, filed January 23, 1928, Patent No. 1,708,675, April 9, 1929, and is similar in some respect to the knitting needles disclosed in the copending application of 5 William H. Leavin and Samuel B. Leavin, Serial No. 293,430, filed July 17, 1928.

This invention relates to a form of knitting needle for use in a machine described in the above entitled application in which the hook 10 portion is offset in a particular manner from the straight shank portion of the needle.

Another object of this invention relates to knitting needles of the above type which are adapted to efficiently and rapidly repair runs 20 in fabrics without the danger of skipping some of the threads which cross the run to be repaired and thereby leave unsightly marks or holes in the fabric being repaired.

These and other objects as will appear 25 from the following disclosure are secured by means of this invention.

This invention resides substantially in the combination, construction, arrangement and relative location of parts as will appear more 30 fully hereinafter.

Referring to the drawings: There is shown 35 a side elevational view in Figure 1 of one form of needle having an inclined portion, and

Fig. 2 is a side elevational view of a modified form of needle showing the shank constructed with a long curved portion.

As shown in Fig. 1, one form of needle is 40 shown having a straight shank portion 1 and an inclined portion 2 connected to the shank 1 and lying at an angle in respect thereto. The inclined portion at one end runs into a sharp curve 2' and terminates in a straight portion 3' thereby forming a hook. The inclined portion 2 is provided with two parallel ears 3 which are supported to form the slot 4. Pivots mounted in the slot 4 is a latch member 5 of such length as to contact 45 with the end of the straight portion 3' when the latch is closed. The latch is provided at

the pivoted end with a projecting cam surface 6 which contacts with the free end of a spring 7. The free end of the spring 7 lies in the slot 4 as shown in Fig. 1. The spring 7 acts on the cam surface 6 to hold the latch 55 member in either open or closed position under a slight tension.

In the form of needle shown in Fig. 2 the straight shank portion 8 runs into a long curved portion 9 which extends directly to 60 the sharply curved portion 10 which in combination with the straight portion 11 forms a hook as shown. The construction of the latch 5, the ears 3 and the spring 7 is the same as that shown in Fig. 1.

It is not attempted to disclose in detail the use of the needle in this application since this has been carefully set forth in the copending application of William H. Leavin and Samuel B. Leavin, Serial No. 293,430, 70 referred to above. There has likewise been disclosed in that application the advantages of the offset portion of the needle of which one form is disclosed therein. In general, it may be stated that having the hook portion offset from the straight portion of the shank it insures that the needle will enter between the cross threads in succession during the repairing operation without danger of skipping so as to leave a hole in the fabric. 80

I am well aware that some changes in the detail of construction, relative arrangement of parts and preparations thereof will readily occur to those skilled in the art and I do not, therefore, desire to be strictly limited 85 to the structure disclosed for purposes of illustration but rather to the scope of the invention as set forth in the appended claims.

What I seek to secure by United States Letters Patent is:

1. In a knitting needle of the type described, the combination comprising a straight shank portion, a long inclined slotted portion connected to the shank and lying at an angle in respect thereto, a hooked shaped portion attached to the angularly inclined portion said hooked shaped portion being sharply curved at the point of attachment with the long inclined portion and terminating in a straight portion which extends at an 100

angle to the axis of the straight shank portion, a latch member having one end formed with a cam surface and pivoted in the slot of the inclined portion at such a point that its free end will contact with the end of the straight portion of the hook when the latch is closed, and a spring secured in the slot of the inclined portion which is adapted to engage the cam surface of the latch to hold said latch in open position under a slight tension when the latch is moved from closed to open position.

2. In a knitting needle of the type described, the combination comprising a straight shank portion, a slotted long curved portion connected to the shank, a hooked shaped portion attached to the long curved portion being sharply curved at the point of attachment with the long curved portion and terminating in a straight portion, a latch member having one end formed with a cam surface and pivoted at that point in the slot of the long curved portion so that its free end will contact with the end of the straight portion of the hook when the latch is closed, and a spring secured in the slot of the long curved portion which is adapted to engage the cam surface of the latch to hold the latch in open position under a slight tension when the latch is moved from closed to open position.

In witness whereof I have hereunto set my hand on this 31st day of July, A. D. 1928.

RICHARD K. HOHMANN.
